UNITED STATES PATENT OFFICE.

WILLIAM S. HADAWAY, JR., OF NEW ROCHELLE, NEW YORK.

ELECTRIC HEAT-CONTROL SYSTEM FOR TYPE-CASTING MACHINES.

Application filed September 6, 1921. Serial No. 498,820.

This invention relates to heaters for linotype machines, and more particularly to improvements in heat generation and in distribution and control of operating media 5 for type-casting machines and the like.

Broadly stated, it is the object of the present invention to provide a system of heating for type-casting machines, of improved efficiency; and to reduce the operating 10 costs of such machines by providing for each of the parts and cooperating members heating means most suitable for that part.

Another object is to provide a plurality of pots supplied with a heating medium by 15 a master heat generator, with means in each of the pots for melting the metal or other working material, and also means operable by the same generator for refining the material to prepare the same properly for use 20 in the pots.

Another object relates to an improved form of refining furnace in which the refining of the working material is accomplished with the amount of heat necessary for that 25 purpose with means for controlling the temperature using a great proportion of low cost heat, and a smaller proportion of relatively high cost heat, and employing the products resulting therefrom to prepare the 30 working material finally for use in casting.

Still another object relates to a device for liquefying metal, whereby incoming heat transferring medium is caused to actuate the device and before being exhausted is caused 35 to pass through a heat exchange chamber, so as to give up practically all its heat to the work.

Another feature relates to a linotype pot adapted to deliver molten metal to a type casting device, and provided with a throat of improved efficiency.

A further object relates to a melting pot in which a major actuating medium is employed for obtaining an approximation of a predetermined degree of heat, and an additional medium is employed variably to obtain accurate adjustment to a desired temperature. The first named medium has a low cost characteristic and the second is

easily controlled, thus combining the desirable features of both in obtaining an efficient and inexpensively operated device. 50

Another object relates to means whereby the level of the metal in the several crucibles is held uniform with that of the master melting and tempering pot. 55

Another object relates to supplying molten metal continuously to each of the crucibles connected to the master supply, whereby attendant labor costs are reduced 60 and a maximum degree of uniformity of temperature is maintained at all points of the system.

Still another object relates to tempering the metal and regulating the temperature thereof by means of a master temperature controller co-operating with the master melting pot, whereby the use of individual temperature controllers may be obviated if 65 desired. 70

Another object relates to a heating system wherein electricity is employed to actuate and control the burning of fuel; the combustion products and heat resulting therefrom are further utilized in combination with electroresponsive means for supplying heat to a plurality of utilities spaced from the fuel burning apparatus. 75

Another object relates to a system for supplying heat to a group of type casting machines, as well as molten metal from a master heater adapted for individual operation and control of one or more of the type casting machine elements, whereby the separate requirements of one of such machines 80 may be fulfilled independent of other portions of the system. 85

Another object relates to the use of crucibles of reduced size whereby the heat losses are materially lessened thereby increasing 90 the efficiency of the system.

Still another object relates to the distribution of the working material whereby molten metal is transferred from the refining furnace to the individual pots. According to this feature, the metal is subject during its transition through the system to the action of the heat transferring 95

medium being transmitted from the master furnace to heat the pots. Thus the metal is kept in a fluid state and readily flows through the system.

5 Other objects will appear as the description of the invention progresses.

Referring to the drawings—

Fig. 1 shows a source of steam, a heat generator and distributing means.

10 Fig. 2 shows one of the melting pots and temperature regulating mechanism therefor.

Fig. 3 shows a section of a distributing channel.

15 Fig. 4 shows a branch tap connected to the main channel.

Fig. 5 shows the construction of the heat exchange member.

20 Fig. 6 shows the superheater and a wiring diagram of the electrical apparatus.

25 Fig. 7 is an end view of the mouthpiece of a melting pot.

Like characters of reference indicate corresponding parts throughout all the figures of the drawings.

25 Referring to the drawings, one embodiment of my invention comprises a heat generator having an outer casing 10 of refractory material open at the top, the outer surface of which may be covered with metal as shown at 11. An inner casing 20 is made of similar refractory material, and is also open at the top, and fits within the outer casing. A receptacle 30 of refractory material, also open at the top, fits within this inner casing, and is provided with a flange 31 near its upper end which fits an annular groove in the inner casing to position the receptacle. A plurality of passages such as 40 extends from the upper portion of the device to the outlet 41.

40 A member 45 is formed in a shape to correspond with that of the top of the casing 10 and forms a seal therefor. Said member may be made of cast iron or other suitable material and has a relatively thick bottom portion 46 adapted to diffuse heat. The side walls 47 extend upwardly a suitable distance to form a vat of a desired capacity for refining pigs and slugs of metal to be used in the typesetting operation and are hollow to form an annular chamber in which is supported a continuous passage 151 interconnecting the outlet 41 with an exterior pipe 150. Thus additional surface is secured whereby the heat of the vapor and gases in the passage may be imparted to the metal in the vat, as will be set forth subsequently.

60 Within the inner casing 20 and below the receptacle 30 is formed a heat generating chamber. A plurality of vapor heaters is placed within this chamber. In the present embodiment two such heaters are shown designated by the reference numerals 50 and 51. These rest upon ledges formed on the

inner surface of the inner casing in such a way as to hold them transversely across the chamber so that they divide the chamber into three compartments 52, 53 and 54. These vapor heaters comprise porous body portions 55 in which are embedded electrical heater elements 56 and 57. A practical form of vapor heater for this purpose is described in detail in Patent No. 1,349,131 issued to me 70 August 10, 1920.

75 The lower part of the receptacle is of reduced diameter and through this part extends transversely a hollow dissociation heater or glower 32. This is a perforated tube preferably in the form of a fulgurite 60 and made of oxides of magnesia or other material which may be operated at a glowing temperature and which is a conductor of electricity only when hot.

80 The electrical connections of the dissociation heater 32 and the heater elements 56, 57 with a source of electric current may be made in any desired manner, as for example as shown in Fig. 3 of my copending application Serial No. 389,545, filed June 17, 90 1920, electric furnaces.

95 In the outer surface of the inner casing 20 is a spiral groove 21 with the lower end of which is connected an air inlet 22 which may be controlled by a valve 23. An annular groove 24 in the inner surface of the inner casing is connected with the upper part of the spiral groove 21 by radial passages 25. Radial passages 33 through the receptacle connect groove 24 with the space within the receptacle. An air pump or blower 26 is provided to cause a current of air to be supplied to these passages.

100 The inlet 14 is connected by a pipe 60 to a suitable source 61 of hot vapor. The outlet 41 is connected to the passage 151, exterior pipe 150 and thence to a pipe 64 which forms a part of a main line distributing pipe 62 and through subsidiary taps or branches such as 63 to a plurality of utilities such as 70, 79. The pipe 64 is enclosed within the pipe 62. In the present embodiment the utilities comprise melting pots for linotype machines and machines of like character. The distributing channel may extend to as many such devices as required, and these devices may be arranged in any desired combinations and locations, subject only to the capacity of the system.

110 The level of the liquid within the member 45 is preferably adjusted with reference to the level of the molten metal within the receptacles 88 of the crucibles described below so as to insure flow by gravity through the system. The drawings show this arrangement more or less diagrammatically, it being understood that in practice the member 45 may be on a level with the utilities or may be in any other desired relation therewith instead of as shown.

The regulator bulb 170 is provided within the member 45 for a purpose which will be described subsequently.

As shown in Fig. 4 of the drawings, the channel 62 and tap 63 comprise the conducting pipe 64 and a passage 152 spaced therefrom protected by a covering or jacket 65 in which is supported a plurality of conductors 66, 67 in spaced relation with each other 10 and with the pipe 64 so as to be electrically insulated.

Other forms of the distributing pipe 62 and taps 63 are shown in Patent 1,383,107 issued to me June 28, 1921.

15 The pipe 64 is joined to an ordinary pipe T 68 whereby a tap may be taken off at an angle. The packing 65 is slightly enlarged and suitably formed to enclose this T. On one side of the T on the main line, and 20 spaced apart therefrom on the branch line are the binding posts 69, 69 electrically insulated, which are connected with the internal wires 66, 67. Suitable jumpers are provided between the respective pairs of 25 binding posts whereby main line conductors 66, 67 are connected to corresponding conductors in the branch tap. Each of the conductors of the branch tap is terminated on similar insulated binding posts 59, positioned relatively near the utility. Said 30 binding posts 59, 59 may be connected to a control switch separably operable or actuated automatically by a shut off valve 71 as desired. Thus the circuit through the conductors of a branch tap may be opened or 35 closed in a convenient manner and the vapor shut off from the utility.

The resistance of the conductors in the branch taps of the system may either be 40 similar to or different from those of the main line. I prefer to provide conductors of higher resistance per unit length in the branch tap relative to the main line. In other cases, the conductors may be omitted 45 in the main line, where type casting machines are few in number and the main line relatively short, or omitted altogether where the temperature of the heating medium is sufficiently high to render the electrical heating 50 means unnecessary.

The interior of the vat 45 is connected by a radial passage 155 to an exterior pipe 156 leading to the passage 152, which as shown in Fig. 4, is connected to taps 156 corresponding to the taps 63. Valves may be provided at the points 157 for shutting off the 55 passages when desired.

At the end of each of the branch taps 63 away from the main channel 62 is a utility 60 such for example as a type casting melting pot 79 (Fig. 2). That shown comprises a body portion 80 and an outer shell 81 with insulation 82 between them.

65 The crucible comprises a chamber 83 having a piston 160 secured to an actuating rod

161. Supported in the insulation 82 near the walls of the crucible is a heater 86 which will be more fully described later. The crucible is provided with a well 162 and a throat 84 through which its contents are ejected upon downward movement of the piston 160. The body portion 80 has a top plate 85 forming a cover in fixed position.

70 Mounted within the pot is a receptacle 88 having an aperture 89 through its bottom surface, which is positioned immediately above the chamber 83. Said receptacle 88 is suitably supported, as for example, by means of a flange 91 which may rest upon the rim of the pot. A removable lid 93 is provided 75 for giving access to the interior. For introducing metal into the receptacle 88, the branch tap passage 156 is led through the wall portion of the crucible and is arranged to discharge into the interior of the receptacle. The drawings show the distributing pipes in schematic form, it being understood 80 that any suitable arrangements may be employed.

85 The form and capacity of the receptacle 88 may of course be varied considerably from the specific proportions illustrated, depending upon the requirements of the work. It may, if necessary extend above the top 90 85, the cover 93 then being adapted to fit the top of the receptacle.

95 The receptacle 88 comprises two nesting cup shaped shells secured together at their edges, preferably by being welded. Around the sides and bottom thereof, and between said enclosing shells is a double pipe forming a heat exchange member. This heat exchange member is shown diagrammatically in unbent form in Fig. 5, and comprises 100 an inner pipe or vapor conductor 101 joined at one of its ends 102 to the heat generator by means of the vapor conductors 62, 63 already described. Said pipe 101 is of smaller diameter than the casing 103 coextensive therewith, and is held in spaced relation therewith by a porous mass 104, preferably of granular carborundum or the like. The interior of pipe 101 may 105 be filled with similar material.

110 The heat exchange member just described may be coiled around within the walls of receptacle 88 in helical formation, and in grid like formation within the bottom wall, or it may be bent in U-shaped formation around said receptacle or it may be formed in other suitable shapes so as to be in active relation to the contents of the receptacle. The end 102 of the casing 103 is provided 115 with a plurality of vents such as 105 open to the atmosphere, constructed to permit the escape of vapor while retaining mass 104 in place.

120 The end 106 of pipe 101 is connected by a pipe 107 to the heater 86.

125 The heater 86 is shown diagrammatically

in Fig. 6 and preferably comprises a tubular casing 110 connected at one end to the pipe 107. Within the casing is a porous mass 111 similar to the mass 104. Supported in the mass 111 and electrically insulated thereby from the casing 110 are one or more conductors such as 112, 113. Suitable insulating bushings (not shown) are provided in the casing 110 for the entry 10 of said conductors. The heater 86 is formed into any desired shape and supported in the insulation near the walls of the pot or crucible. The end 114 of the tube 110 is connected to the throat 84, by means of a 15 pipe 115. It is understood that the drawings show the heater 86 and the throat 84 somewhat enlarged to show more clearly these features of the invention.

The throat 84 extends from the well 162 20 to the mouthpiece 120 and is slightly curved as shown in the drawings. Surrounding the throat is a heater passage 121 which may extend only above the main passage way of the throat, or only below it, or on 25 either or both sides or may surround it. As shown a helical passage surrounds the throat from its base to its mouth, and is connected by a passage 122 to the end 106 of the casing 103.

30 The passageway 121 shown may be formed at the time the throat structure is cast by employing a core made of tubing filled with carborundum or the like. Thus the carborundum core is positioned within the 35 casting and in operation forms a passage for the conduction of vapors and gases, substantially helical in form. Another modification comprises a coil formed to enclose the throat structure by being wrapped around 40 the outside of the throat.

The mouthpiece is positioned to deliver molten metal through the cavity of a mold wheel (not shown) to a type casting device.

45 Above the mouthpiece 120 is a transverse enlargement 123 through an aperture of which extends a mercury bulb 124. By means of a tube 125, said bulb is operatively connected to a regulator 130, which 50 may be of the form shown in Patent 1,282, 221 issued to me on October 22, 1918.

Said regulator comprises a casing 131 55 mounted in any desired manner, in which is supported a mechanism responsive to expansion and contraction of the mercury in the bulb 124. The mechanism is constructed to open contacts 133 when the mercury expands a predetermined amount from a set standard, and to close contacts 134 when 60 a predetermined amount of contraction takes place. Adjustments are provided for varying the set standard when desired.

As shown in the wiring diagram of Fig. 6 the contacts 133 are included in circuit 65 with a conductor 112 while contacts 134

are in circuit with a conductor 113. A generator 137 energizes these circuits and a switch 138 cuts off the current when the device is shut down. In Fig. 2 the conductor 113 is omitted for the sake of simplicity. It is obvious that this or any other desired electrical means may be employed without departing from the spirit of the invention.

A regulator bulb 170 similar to the bulb 124 is provided in connection with the vat 45 to control a regulator 171 similar to the regulator 130. The operation of this regulator according to changes in temperature of the metal within the vat controls the electrical connections to the heaters within the chamber 52 of the master furnace and thus the temperature of the metal may be predetermined with accuracy by an adjustment of the regulator 171. It is understood that the system may be operated with regulators 171 and 130 for controlling the master furnace and the individual utility respectively or only the regulator 171 may be employed, thereby greatly reducing the number of regulators required; or only the regulators 130 may be employed, thus providing for work of unlike character at the various utilities. An extremely flexible system is thereby obtained which may be employed for a variety 95 of purposes. For example, in newspaper work it is desirable to produce type molds at a very high speed and of a uniform character; in this case regulator 171 would be employed and regulators 130 would be dispensed with. In a job printing shop, however, a number of varieties of type molds would have to be cast in accordance with the different grades and qualities of work being put through the shop at a given time; in 100 this case regulators 130 would be employed and the regulator 171 would be dispensed with.

Still another form of installation might 110 require the combinations of the two systems just described.

In operation, hot vapor is supplied from the source 61 to the furnace or heat generator. An electric current is caused to flow temporarily through vapor heaters 50, 51. 115 The vapor being admitted by way of inlet 14 passes through vapor heater 50 and is superheated thereby. It then passes through vapor heater 51 and is again heated and subsequently passes into receptacle 30 through the dissociation heater 32. The heated vapor heats the fulgurite tube 32 sufficiently to make it a conductor of electricity and the temperature of the tube is raised to the glowing point by an electrical current passing through it. This degree of heat is sufficient to dissociate the vapor, breaking it up into its constituent elements, hydrogen and oxygen, and the oxygen is recombined with the contents 34 of receptacle 30 by com- 120 125 130

bustion. The dissociation of the vapor takes up heat and serves as an automatic means for preventing an indefinite increase in the temperature of the tube 32. I have 5 found that the vapor is not entirely dissociated, and in the present invention I employ the unconsumed vapor together with the gaseous combustion products for the additional purpose of transferring and 10 changing heat, as will be set forth subsequently.

When the valve 23 is open, air will be admitted to the receptacle and into the flame which will unite with the burning gases and 15 further increase their temperature. In doing this the air will circulate in the spiral groove 21 where it will become pre-heated to a certain extent and will at the same time increase the heat insulating effects of the 20 casings 10 and 20.

The gases resulting from the action just described together with the uncombined vapor find a path of escape through the passages 41, 150 into the conduit 64 of the main 25 distributing pipe 62 and to the several utilities connected thereto.

A source of current 140 is connected to the conductors 66, 67 through a switch 141.

The circuit between the binding posts 59, 30 59 adjacent to the melting pot 79 is now closed manually; or if desired, it may be done automatically by the use of a switch operated by the valve 71. The valve 71 is placed in its open position. The vapor now 35 flows into the heat exchange member 101 of the receptacle 88. Emerging therefrom it flows through passage 107 to the vapor heater 86, where it becomes superheated; switch 138 having been closed, an actuating 40 current flows through the circuit; generator 137, switch 138, conductor 150 (Fig. 2) contact 134 of regulator 131 (closed at low temperatures), conductor 151, conductor 113, to the opposite pole of generator 137.

45 The superheated vapor flows through the passage 115 to the throat heating passage 121; then through passage 122 to the outer casing 103 of the heat exchange chamber, whence it escapes to the atmosphere through 50 vents 105, as shown in Fig. 5.

The vessel 45, in combination with the high efficiency heat generator forms a convenient, simple and economical means of refining the metal. The metal is placed in 55 the vessel 45, and the heat of the generator causes the metal to melt. The refined metal then flows through the system into the wells 83.

60 The metal is heated to a predetermined degree of heat according to the adjustment of the regulator 130. In the arrangement of Fig. 6, the contact 134 remains closed until the predetermined temperature is attained, whereupon the circuit of heat generating

conductor 113 is broken. The working heat 65 is maintained by the heat dissipated by the other conductor 112. If for any reason the temperature becomes greater than a predetermined amount regulator 130 causes the contact 133 to be opened, thus breaking the 70 circuit of conductor 112 until the mouthpiece 120 cools off slightly. If, for any reason, the temperature falls below the predetermined point, the contact 134 closes the circuit of heat generating conductor 113 to 75 heat the superheater rapidly, until the temperature is restored.

The molten metal is discharged from mouthpiece 120 into the type casting device.

It should be noted that before the gases 80 finally escape, their heat is utilized to the utmost degree in being exchanged in the chamber 103, so that a minimum loss of energy results.

The structure provides the proper degree 85 of heat for each of the stages of the operation, with a single operating system of heat generation and distribution.

While I have shown one form of the invention for the purpose of illustration and 90 description, it will be understood that the scope of the invention is not to be limited thereby, reference being had to the appended claims for that purpose.

95 What I claim is:

1. In a heating system for a type casting machine, an electric furnace for refining the working metal comprising a fuel combustion chamber, an electric glower therein, and means for passing a vapor through said 100 glower into fuel in the combustion chamber, means for passing the unconsumed vapor from said furnace to said machine, and a heater for said machine operated by said unconsumed vapor to finally prepare the work- 105 ing metal for use in the machine.

2. In a heating system for type casting machines, an electric furnace for refining the working metal comprising a fuel combustion chamber, an electric glower therein, and 110 means for passing a vapor through said glower into fuel in the combustion chamber, means for passing the unconsumed vapor from said furnace to said machines, and a heater for each of said machines operated by said unconsumed vapor to finally prepare the working metal for use in the machine.

3. In a heating system for a type casting machine, an electric furnace for refining the working metal comprising a fuel combustion 120 chamber, an electric glower therein, and means for passing a vapor through said glower into fuel in the combustion chamber, said glower being arranged to raise the temperature of the vapor to a point above the ignition point of the fuel, means for passing the unconsumed vapor from said furnace to said machine, and a heater for said machine 125

3
operated by said unconsumed vapor to finally prepare the working metal for use in the machine.

4. In a heating system for type casting machines, an electric furnace for refining the working metal comprising a fuel combustion chamber, an electric glower therein, and means for passing a vapor through said glower into fuel in the combustion chamber, said glower being arranged to raise the temperature of the vapor to a point above the ignition point of the fuel, means for passing the unconsumed vapor from said furnace to said machines, and a heater for each of said machines operated by said unconsumed vapor to finally prepare the working metal for use in the machine.

5. In a heating system for a type casting machine, an electric furnace for refining the working metal comprising a fuel combustion chamber, an electric glower therein, which is a non-conductor of electricity at ordinary temperatures but a conductor when hot, and means for passing hot vapor through said glower into fuel in the combustion chamber, means for passing the unconsumed vapor from said furnace to said machine, and a heater for said machine operated by said unconsumed vapor to finally prepare the working metal for use in the machine.

6. In a heating system for type casting machines, an electric furnace for refining the working metal comprising a fuel combustion chamber, an electric glower therein, which is a non-conductor of electricity at ordinary temperatures but a conductor when hot, and means for passing hot vapor through said glower into fuel in the combustion chamber, means for passing the unconsumed vapor from said furnace to said machines, and a heater for each of said machines operated by said unconsumed vapor to finally prepare the working metal for use in the machines.

7. In a heating system for a type casting machine, an electric furnace for refining the working metal comprising a fuel combustion chamber, an electric glower therein, which is a non-conductor of electricity at ordinary temperatures but a conductor when hot, and means for admitting air to the combustion chamber, means for passing the unconsumed vapor from said furnace to said machine, and a heater for said machine operated by said unconsumed vapor to finally prepare the working metal for use in the machines.

8. In a heating system for type casting machines, an electric furnace for refining the working metal comprising a fuel combustion chamber, an electric glower therein, which is a non-conductor of electricity at ordinary temperatures but a conductor when hot,

and means for admitting air to the combustion chamber, means for passing the unconsumed vapor from said furnace to said machines, and a heater for each of said machines operated by said unconsumed vapor to finally prepare the working metal for use in the machines.

9. In a heating system for a type casting machine, an electric furnace for refining the working metal comprising a fuel combustion chamber, an electric glower therein, and means for admitting air to the combustion chamber, means for passing the unconsumed vapor from said furnace to said machine, and a heater for said machine operated by said unconsumed vapor to finally prepare the working metal for use in the machine.

10. In a heating system for type casting machines, an electric furnace for refining the working metal comprising a fuel combustion chamber, an electric glower therein, and means for admitting air to the combustion chamber, means for passing the unconsumed vapor from said furnace to said machines, and a heater for each of said machines operated by said unconsumed vapor to finally prepare the working metal for use in the machine.

11. In a heating system for a type casting machine, an electric furnace for refining the working metal comprising a fuel combustion chamber, an electric glower therein, and means for passing a vapor through said glower into fuel in the combustion chamber, a conducting passage for passing the unconsumed vapor from said furnace to said machine, a heater for said machine operated by said unconsumed vapor to finally prepare the working metal for use in the machine, and electric heat generating conductors in said passage for raising the temperature of the vapor.

12. In a heating system for type casting machines, an electric furnace for refining the working metal comprising a fuel combustion chamber, an electric glower therein, and means for passing a vapor through said glower into fuel in the combustion chamber, a conducting passage for passing the unconsumed vapor from said furnace to said machines, a heater for each of said machines operated by said unconsumed vapor to finally prepare the working metal for use in the machine, and electric heat generating conductors in said passage for raising the temperature of the vapor.

13. In a heating system for type casting machines, an electric furnace for refining the working metal comprising a fuel combustion chamber, an electric glower therein, and means for passing a vapor through said glower into fuel in the combustion chamber, a conducting passage for passing the un-

- consumed vapor from said furnace to said machines, a heater for each of said machines operated by said unconsumed vapor to finally prepare the working metal for use in the machine, electric heat generating conductors in said passage for raising the temperature of the vapor, a shut-off valve to disconnect at least one of said heaters, and means to automatically control the current in said electric heat generating conductors proportionally to the number of active heaters.
14. In a heating system for type casting machines, an electric furnace for refining the working metal comprising a fuel combustion chamber, an electric glower therein, and means for passing a vapor through said glower into fuel in the combustion chamber, a conducting passage for passing the unconsumed vapor for said furnace to said machines, a heater for each of said machines operated by said unconsumed vapor to finally prepare the working metal for use in the machine, electric heat generating conductors in said passage for raising the temperature of the vapor, a shut-off valve to disconnect each of said heaters independently, and means actuated by said valve to automatically open the circuit of at least a portion of said conductors.
15. A heating system for type casting machines, comprising an electric furnace for refining the working metal and a crucible actuated by heat from said furnace said crucible having a chamber adapted to receive melted metal from said furnace, and an automatic regulator responsive to variations in temperature of said furnace for variably controlling said furnace.
16. A heating system for type casting machines comprising an electric furnace for refining the working metal and a plurality of non-contiguous crucibles actuated by heat from said furnace each having a chamber adapted to receive melted metal from said furnace, and an automatic regulator responsive to variations in temperature of said furnace for variably controlling said furnace.
17. The combination with a metal working machine, a liquefying pot for said machine a heat exchange member for said pot adapted to maintain liquefaction, of a master furnace to supply heat transferring medium for the pot and to refine metal for use in said pot.
18. The combination with a plurality of metal working machines, a liquefying pot for each of said machines, a heat exchange member for each of said pots adapted to maintain liquefaction, of a master furnace to supply heat transferring medium for the pots and to refine metal for use in said pots.
19. The combination with a metal work-
- ing machine, a liquefying pot for said machine, a heat exchange member for said pot adapted to maintain liquefaction, of a master furnace to supply heat transferring medium for the pot and to refine metal for use in said pot, and conducting means for transferring the medium from said furnace.
20. The combination with a plurality of metal working machines, a liquefying pot for each of said machines, a heat exchange member for each of said pots adapted to maintain liquefaction, of a master furnace to supply heat transferring medium for the pots and to refine metal for use in said pots, and conducting means for transferring the medium from said furnace.
21. The combination with a plurality of type setting machines; a melting pot for each of said machines comprising a receptacle for type metal, a heat exchange member within the walls of said receptacle, said receptacle having a perforated bottom; a chamber positioned beneath a perforation in the bottom of the receptacle, said chamber having an electrical vapor heater adjacent thereto and a throat for withdrawing the contents of said chamber; a source of heat transferring medium, conducting means for transferring vapor to said melting pots; of a master furnace to heat the vapor for rendering the pots active and to refine the metal for use in said pots.
22. The combination with a plurality of type casting machines; a corresponding number of melting pots for supplying molten metal to said machines, each comprising a receptacle having a perforated bottom and adapted to be suspended in the body of the pot to receive metal, a heated throat for discharging the metal and a heated well positioned beneath the perforation in the bottom of said receptacle for heating the metal; and a source of heat transferring medium and means for conducting said medium to said melting pots; of a single furnace adapted to heat the medium and to refine the metal for use in said pots.
23. The combination with a plurality of type setting machines, a corresponding number of melting pots for supplying molten metal to said machines, each comprising a receptacle having a perforated bottom and double walls enclosing a tortuous heat exchange member for conducting heat transferring medium and adapted to be suspended in the body of the pot to receive metal, a throat for discharging the metal to the type setting machine, a passage adjacent said throat for conducting the medium for heating the throat, and a well positioned beneath the perforation in the bottom of said receptacle, an electrically heated passage adjacent said well for conducting the medium for heating the well; and a source of heat transferring medium and means for

conducting the medium to the inlet passage of said heat exchange member, the welt passage, throat passage and outlet passage of said heat exchange member in order; of 5 a single furnace adapted to superheat said medium before its passage to said passages and to refine the metal for use in said pots.

24. In a heating system for type casting machines, an electric furnace for refining 10 the working metal comprising a refining pot having a heat exchange chamber, a fuel combustion chamber in active relation with said pot, an electric glower therein, and means for passing a vapor through said 15 glower into fuel in the combustion chamber, means for passing the unconsumed vapor from said furnace through the heat exchange chamber and thence to said machines, a heater for each of said machines 20 operated by said unconsumed vapor to finally prepare the working metal for use in the machine.

25. In a heating system for a type casting machine, an electric furnace for refining the 25 working metal comprising a refining pot having a heat exchange chamber, a fuel combustion chamber in active relation with said pot, an electric glower therein, and means for passing a vapor through said 30 glower into fuel in the combustion chamber, means for passing the unconsumed vapor from said furnace through the heat exchange chamber and thence to said machine, a heater for said machine operated by said 35 unconsumed vapor to finally prepare the working metal for use in the machine, and conducting means for transferring metal from the master furnace to said pots.

26. In a heating system for type casting machines, an electric furnace for refining 40 the working metal comprising a refining pot having a heat exchange chamber, a fuel combustion chamber in active relation with said pot, an electric glower therein, and 45 means for passing a vapor through said glower into fuel in the combustion chamber, means for passing the unconsumed vapor from said furnace through the heat exchange chamber and thence to said machines, 50 a heater for each of said machines operated by said unconsumed vapor to finally prepare the working metal for use in the machine, and conducting means for transferring metal from the master furnace to said 55 pots.

27. In a heating system for a type casting machine, an electric furnace for refining the 60 working metal comprising a refining pot having a heat exchange chamber, a fuel combustion chamber in active relation with said pot, an electric glower therein, and means for passing a vapor through said 65 glower into fuel in the combustion chamber, means for passing the unconsumed vapor from said furnace through the heat ex-

change chamber and thence to said machine, a heater for said machine operated by said unconsumed vapor to finally prepare the working metal for use in the machine, and conducting means for transferring metal 70 from the master furnace to said pots comprising an elongated heat exchange chamber.

28. In a heating system for type casting machines, an electric furnace for refining 75 the working metal comprising a refining pot having a heat exchange chamber, a fuel combustion chamber in active relation with said pot, an electric glower therein, and means for passing a vapor through said glower into fuel in the combustion chamber, 80 means for passing the unconsumed vapor from said furnace through the heat exchange chamber and thence to said machines, a heater for each of said machines operated by said unconsumed vapor to finally prepare 85 the working metal for use in the machine, and conducting means for transferring metal from the master furnace to said pots comprising an elongated heat exchange 90 chamber.

29. In a heating system for a type casting machine, an electric furnace for refining the working metal comprising a refining pot having a heat exchange chamber, a fuel combustion chamber in active relation with said pot, an electric glower therein, and means for passing a vapor through said glower into fuel in the combustion chamber, 95 means for passing the unconsumed vapor from said furnace through the heat exchange chamber and thence to said machine, a heater for said machine operated by said unconsumed vapor to finally prepare the working metal for use in the machine, and conducting means for transferring metal from the master furnace to said pots comprising an elongated heat exchange 100 chamber.

30. In a heating system for type casting machines, an electric furnace for refining

the working metal comprising a refining pot having a heat exchange chamber, a fuel combustion chamber in active relation with said pot, an electric glower therein, and means for passing a vapor through said glower into fuel in the combustion chamber, 110 means for passing the unconsumed vapor from said furnace through the heat exchange chamber and thence to said machines, a heater for each of said machines operated by said unconsumed vapor to finally prepare the working metal for use in the machine, and conducting means for transferring metal from the master furnace to said pots comprising an elongated heat exchange chamber having electro-responsive means for 115 superheating said chamber.

31. The combination with a metal working machine, a liquefying pot for said ma- 120

125

130

chine, a heat exchange member for said pot adapted to maintain liquefaction, of a master furnace to supply heat transferring medium for the pot and to refine metal for use in said pot, and conducting means for transferring metal and heat transferring medium from the master furnace to said pot.

32. The combination with a plurality of metal working machines, a liquefying pot for each of said machines, a heat exchange member for each of said pots adapted to maintain liquefaction, of a master furnace to supply heat transferring medium for the pots and to refine metal for use in said pots, and conducting means for transferring metal and heat transferring medium from the master furnace to said pots.

33. The combination with a plurality of metal working machines, a liquefying pot for each of said machines, a heat exchange member for each of said pots adapted to maintain liquefaction of a master furnace to supply heat transferring medium for the pots and to refine metal for use in said pots, and conducting means for transferring metal and heat transferring medium from the master furnace to said pots comprising an elongated heat exchange chamber.

34. The combination with a metal working machine, a liquefying pot for said machine, a heat exchange member for said pot adapted to maintain liquefaction, of a master furnace to supply heat transferring medium for the pot and to refine metal for use in said pot, and conducting means for transferring metal and heat transferring medium from the master furnace to said pot comprising an elongated heat exchange chamber having electro-responsive means for superheating the heat transferring medium.

35. The combination with a plurality of metal working machines, a liquefying pot for each of said machines, a heat exchange member for each of said pots adapted to maintain liquefaction, of a master furnace to supply heat transferring medium for the pots and to refine metal for use in said pots, and conducting means for transferring metal and heat transferring medium from the master furnace to said pots comprising an elongated heat exchange chamber having electro-responsive means for superheating the heat transferring medium.

36. The combination with a type casting machine melting pot constructed to use vapor as an actuating element, of a furnace for heating vapor and for refining type metal and conducting means for transmitting said vapor and said metal from the furnace to the pot.

37. The combination with a plurality of type casting machine melting pots constructed to use vapor as a heating medium, of a furnace for heating vapor and for re-

fining type metal and conducting means for transmitting said vapor and said metal from the furnace to the pot.

38. The combination with a type casting machine melting pot constructed to use vapor as a heating medium, of a furnace for heating vapor and for refining type metal and a double pipe for transmitting said vapor and said metal from the furnace to the pot.

39. The combination with a plurality of type casting machine melting pots constructed to use vapor as a heating medium, of a furnace for heating vapor and for refining type metal and a double pipe for transmitting said vapor and said metal from the furnace to the pots.

40. The combination with a type casting machine melting pot constructed to use vapor as a heating medium, of a furnace for heating vapor and for refining type metal, a double pipe for transmitting said vapor and said metal from the furnace to the pot, and electro-responsive means in active relation with said pipe to superheat said vapor.

41. The combination with a plurality of type casting machine melting pots constructed to use vapor as a heating medium, of a furnace for heating vapor and for refining type metal, a double pipe for transmitting said vapor and said metal from the furnace to the pots, and electro-responsive means in active relation with said pipe to superheat said vapor.

42. A furnace for refining metal and heating vapor, a type casting machine melting pot actuated by heated vapor to prepare metal for casting type, conducting means for transferring said vapor and metal from the furnace to the pot comprising a heat exchange chamber for maintaining the temperature at an approximation of a predetermined temperature, and means for conducting to said heat exchange chamber an electric current for varying the degree of heat for obtaining substantially the desired temperature.

43. A furnace for refining metal and heating vapor, a plurality of type casting machine melting pots actuated by heated vapor to prepare metal for casting type, conducting means for transferring said vapor and metal from the furnace to the pots comprising a heat exchange chamber for maintaining the temperature at an approximation of a predetermined temperature, and means for conducting to said heat exchange chamber an electric current for varying the degree of heat for obtaining substantially the desired temperature.

44. In a heat control system for type casting machines, a type casting melting pot, a master furnace to refine metal and to supply heat to a heat transferring medium,

conducting means for transferring metal from the furnace to the pot arranged to maintain the metal at an approximation of a desired temperature by means of the 5 heat transferring medium and to conduct said medium from the furnace to the pot, and means for conducting adjacent said double conducting means, a second medium of unlike character for varying the degree 10 of heat to obtain substantially the desired temperature.

45. In a heat control system for type casting machines, a plurality of type casting melting pots, a master furnace to refine 15 metal and to supply heat to a heat transferring medium, conducting means for transferring metal from the furnace to the pots arranged to maintain the metal at an approximation of a desired temperature by 20 means of the heat transferring medium and to conduct said medium from the furnace to the pots; and means for conducting adjacent said double conducting means a second medium of unlike character for varying 25 the degree of heat to obtain substantially the desired temperature.

46. In a heat control system for type casting machines, a type casting machine melting pot, a master furnace to refine metal 30 and to supply heat to a heat transferring medium, conducting means for transferring metal from the furnace to the pot constructed to exchange heat from the medium to the metal to maintain the metal at an 35 approximation of a desired temperature, and to conduct said medium from the furnace to the pot; and means for conducting adjacent said double conducting means a second medium of unlike character for varying 40 the degree of heat to obtain substantially the desired temperature.

47. In a heat control system for type casting machines, a plurality of type casting machine melting pots, a master furnace to 45 refine metal and to supply heat to a heat transferring medium, conducting means for transferring metal from the furnace to the pots constructed to exchange heat from the medium to the metal to maintain the metal at an 50 approximation of a desired temperature, and to conduct said medium from the furnace to the pots; and means for conducting adjacent said double conducting means a second medium of unlike character for varying 55 the degree of heat to obtain substantially the desired temperature.

48. In a heat control system for type casting machines, a type casting machine melting pot, a master furnace to refine metal and 60 to supply heat to a heat transferring medium, conducting means for transferring metal from the furnace to the pot constructed to exchange heat from the medium to the metal to maintain the metal at an approximation of a desired temperature, and to con- 65

duct said medium from the furnace to the pot; and means for conducting adjacent said double conducting means an electric current for varying the degree of heat to obtain substantially the desired temperature. 70

49. In a heat control system for type casting machines, a plurality of type casting machine melting pots, a master furnace to refine metal and to supply heat to a heat transferring medium, conducting means for transferring metal from the furnace to the pots constructed to exchange heat from the medium to the metal to maintain the metal at an approximation of a desired temperature, and to conduct said medium from the furnace to the pots; and means for conducting adjacent said double conducting means an electric current for varying the degree of heat to obtain substantially the desired 75 temperature. 80

50. In a heat control system for type casting machines, a plurality of type casting machine melting pots, a master furnace to refine metal and to supply heat to a heat transferring medium, conducting means for transferring metal from the furnace to the pots constructed to exchange heat from the medium to the metal to maintain the metal at an approximation of a desired temperature and to conduct said medium from the furnace to the pots, and an electric heater for varying the degree of heat to obtain substantially the desired 85 temperature. 90

51. A system of heat distribution for a type casting machine comprising a source of heat transferring medium, a furnace actuated partly by said medium and adapted to refine metal for use in the pot, a pot actuated partly by said medium for finally preparing the metal, a passageway for conducting the metal from said furnace to the pot partially heated by said medium, and means for additionally actuating said furnace and heating said passageway and pot by a medium of unlike character. 100 105

52. A system of heat distribution for type casting machines comprising a source of heat transferring medium, a furnace actuated partly by said medium and adapted to refine metal for use in the pots, a plurality of pots actuated partly by said medium for finally preparing the metal, a passageway for conducting the metal from said furnace to the pots partially heated by said medium, and means for additionally actuating said furnace and heating said passageways and pots by a medium of unlike character. 110 115

53. A heating system for type casting machines comprising an electric furnace having a receptacle for refining the working metal, a fuel combustion chamber for heating the receptacle, an electric glower therein and means for passing vapor through said glower into fuel in the com- 120 125 130

bustion chamber, a conducting passage for passing the unconsumed vapor from said furnace to the machines, a crucible for the said machines operated by the unconsumed vapor to finally prepare the working metal for use in the machine, an electric vapor heater for heating the crucible, an automatic regulator responsive to decrease in temperature for controlling said electric glower and additional automatic regulators for said crucibles responsive to decrease in temperature for controlling said electric vapor heater.

54. A heating system for type casting machines comprising an electric furnace having a receptacle for refining the working metal, a fuel combustion chamber for heating the receptacle, an electric glower therein and means for passing vapor through said glower into fuel in the combustion chamber, a conducting passage for passing the unconsumed vapor from said furnace to the machines, a crucible for the said machines operated by the unconsumed vapor to finally 20 prepare the working metal for use in the machine, an electric vapor heater for heating the crucible, an automatic regulator responsive to increase in temperature for controlling said electric glower and additional automatic regulators for said crucibles responsive to increase in temperature for controlling said electric vapor heater.

55. A heating system for type casting machines comprising an electric furnace having a receptacle for refining the working metal, a fuel combustion chamber for heating the receptacle, an electric glower therein, and means for passing vapor through said glower into fuel in the combustion chamber, a conducting passage for passing of unconsumed vapor from said furnace to the machines, a crucible for the said machines operated by the unconsumed vapor to finally 40 prepare the working metal for use in the machine, an electric vapor heater for heating the crucible, an automatic regulator responsive to variations in temperature for controlling said crucibles responsive to variations in temperature for controlling said electric vapor heater.

56. A heating system for type casting machines comprising an electric furnace having a receptacle for refining the working metal, a fuel combustion chamber for heating the receptacle, an electric glower therein, and means for passing vapor through said glower into fuel in the combustion chamber, a conducting passage for passing unconsumed vapor from said furnace to the machines, a crucible for the said machines operated by the unconsumed vapor to finally 55 prepare the working metal for use in the machine, an electric vapor heater for heating the crucible, temperature responsive means responsive to decrease in temperature

for controlling said electric glower and additional temperature responsive means responsive to decrease in temperature for controlling said electric vapor heater.

57. A heating system for type casting machines comprising an electric furnace having a receptacle for refining the working metal, a fuel combustion chamber for heating the receptacle, an electric glower therein, and means for passing vapor through said glower into fuel in the combustion chamber, a conducting passage for passing unconsumed vapor from said furnace to the machines, a crucible for the said machines operated by the unconsumed vapor to finally 70 prepare the working metal for use in the machine, an electric vapor heater for heating the crucible, temperature responsive means responsive to increase in temperature for controlling said electric glower and additional temperature responsive means responsive to increase in temperature for controlling said electric vapor heater.

58. A heating system for type casting machines comprising an electric furnace having a receptacle for refining the working metal, a fuel combustion chamber for heating the receptacle, an electric glower therein, and means for passing vapor through said glower into fuel in the combustion chamber, a conducting passage for passing unconsumed vapor from said furnace to the machines, a crucible for the said machines operated by the unconsumed vapor to finally 80 prepare the working metal for use in the machine, an electric vapor heater for heating the crucible, temperature responsive means responsive to increase in temperature for controlling said electric glower and additional temperature responsive means responsive to increase in temperature for controlling said electric vapor heater.

59. A furnace arranged to heat vapor and to melt metal, a non-contiguous metal working machine, and means for transferring hot vapor and molten metal from the furnace to the machine.

60. A furnace arranged to heat vapor and to melt metal, a plurality of non-contiguous metal working machines, and means for transferring hot vapor and molten metal from the furnace to the machines.

61. A furnace arranged to heat vapor and to melt metal, a non-contiguous metal working machine and a conduit arranged to lead hot vapor and molten metal from the furnace to the machine.

62. A furnace arranged to heat vapor and to melt metal, a non-contiguous metal working machine, a conduit arranged to transfer molten metal from the furnace to the machine, said conduit having a passage for hot vapor from the furnace.

63. A furnace arranged to heat vapor and to melt metal, a plurality of non-contiguous

metal working machines, a conduit arranged to transfer molten metal from the furnace to the machines, said conduit having a passage for hot vapor from the furnace.

5 64. A furnace arranged to heat a gaseous medium and to melt metal, a non-contiguous metal working machine, and means for transferring hot gaseous medium from the furnace to said machine.

65. A furnace arranged to heat a gaseous medium and to melt metal, a plurality of non-contiguous metal working machines, and means for transferring hot gaseous medium from the furnace to said machines.

In witness whereof, I have hereunto set ¹⁵ my hand this 2nd day of September, 1921.

WILLIAM S. HADAWAY, JR.
